UNITED STATES PATENT OFFICE.

CLYDE C. CHARLES, OF SALINA, KANSAS.

FUEL-FEED-VALVE LOCK.

1,300,120.

Specification of Letters Patent.

Patented Apr. 8, 1919.

Application filed November 20, 1918. Serial No. 263,385.

To all whom it may concern:

Be it known that I, CLYDE C. CHARLES, a citizen of the United States, residing at Salina, in the county of Saline and State of 5 Kansas, have invented new and useful Improvements in Fuel-Feed-Valve Locks, of which the following is a specification.

This invention relates to fuel feed valve locks, the broad object in view being to provide means for cutting off the flow of fuel oil in a motor vehicle between the storage tank or reservoir or other source of fuel supply and the carbureter or engine, whereby 10 an unauthorized person is prevented from 15 operating the vehicle and stealing the machine.

The improved fuel feed valve lock is of the combination or permutation variety so that no key is required to be carried by the 20 operator or owner of the machine. It is only necessary for him to know the combination by means of which the several parts of the locking mechanism or the valve may be positioned properly to admit of free 25 flow of the fuel from the tank or reservoir to the carbureter or engine. The locking mechanism is of such a character that it would require a long time on the part of a person unacquainted with the combination 30 to open the valve and obtain the necessary flow of fuel from the tank to the engine, resulting in the detection of any person attempting to operate the lock without being 35 familiar with the combination.

With the above and other objects in view, the invention consists in the novel construction, combination and arrangement of parts herein fully described, illustrated and claimed.

40 In the accompanying drawings;

Figure 1 is a side elevation of the device.

Fig. 2 is a section taken in line with the valve shaft and fuel inlet and outlet passages of the device.

45 Fig. 3 is a plan view of the lower section of the casing showing the opening in the false bottom thereof.

Fig. 4 is a similar view with the tensioning springs in place.

50 Fig. 5 is a horizontal section above the movable tumbler disk, showing the turning means for said disk.

Fig. 6 is a top plan view of the device showing the top bracket and the dial.

55 Referring to the drawings, 1 designates the base or main support of the device, the

same being adapted to be attached to any convenient part of the vehicle, such as the frame, dash or instrument board, said base having a fuel inlet passage 2 and a fuel outlet passage 3. The base is also formed 60 with a disk shaped chamber 3 above which is a disk shaped partition 4 having a central opening or step for the lower end of a tumbler operating shaft 5. The partition 4 is 65 formed with an opening 6 through which the fuel passes from the chamber 3 to the chamber beyond the partition 4.

Fast on the end portion of the shaft 5 is a disk 7 having an opening 8 therein adapted 70 to register with the opening 6 in the partition 4. The disk 7 bears against a shoulder or head 9 at the extremity of the shaft 5 and is held tightly against the same by means of a nut 10 by loosening which the disk 7 may 75 be adjusted axially around the shaft 5 for the purpose of changing the combination. 12 designates a clamp on the end portion of the shaft 5 from which extends a disk operating finger 13 which, when the shaft 5 is 80 turned, is adapted to come in contact with a post 14 extending from the tumbler disk 15 which is mounted loosely for turning movement within the valve casing and provided with an opening 16 adapted to be 85 brought into registration with the opening 6 in the partition 4 and the opening 8 in the disk 7 hereinabove referred to. The rotatable tumbler disk 15 is held against too 90 free rotation by means of one or more tensioning springs 17 fastened to and extending from lugs 18 on the disk 15 and between tensioning posts or lugs 19 from the disk 15 and the inner peripheral wall of the casing.

95 The casing comprises a cylindrical section 20 and a cylindrical section 21. These sections are preferably separate from each other so that they may be disconnected to give access to the locking mechanism contained therein. An expansion spring 22 is interposed between the top of the casing and the disk 7 so as to hold the disk 7 snugly against the tumbler disk 15 and also hold the latter tightly seated against the 100 partition 4 to prevent leakage of gasoline or other fuel oil which would enable the car to be operated.

The shaft 5 extends through a stuffing box 22 carried by the casing and has fast on 110 its upper end a dial 23 and an operating knob 24. The shaft 5 is journaled in a bear-

ing bracket 26 having a finger or pointer 27 to register with the graduations on the dial 23.

From the foregoing description, taken in connection with the accompanying drawings, the operation of the device will now be understood. The knob or handle 24 is grasped and turned in the proper direction so as to cause the tumbler operating finger 10 to engage the post on the tumbler disk 15. The turning movement is continued until the proper graduation on the dial 23 registers with the pointer 27, at which time the hole 16 registers with the hole 6. The knob 15 or handle 24 is then turned in the reverse direction until the proper graduation of the dial is brought into registration with the finger 27 so as to position the hole 8 in the 20 disk 7 in line with the hole 16 of the tumbler disk 15. This provides for a free flow of fuel oil from the tank or reservoir 4 to the engine. When a person is unacquainted with the combination it will take a long time to obtain the flow of fuel oil to the engine, 25 thereby notifying the public that an unauthorized person is tampering with the machine.

I claim:

1. The combination with the fuel feed 30 line of a motor vehicle, of a valve controlling the flow of fuel through said pipe, said valve comprising a casing having a fuel receiving chamber and a fuel inlet passage leading thereto, a partition having a fuel opening 35 therein, a rotatable tumbler disk supported in contact with said partition and having an opening therethrough adapted to register with the aforesaid opening in the partition, a post extending from said tumbler disk, a 40 tumbler operating shaft extending through and projecting from said casing, a disk fast

on the end portion of said shaft and having an opening therethrough adapted to register with the opening in the tumbler disk, a tumbler actuating finger projecting from said 45 shaft and adapted to coöperate with said post on the tumbler disk, the valve casing having an outlet passage leading off from the space beyond said disk, means for turning said tumbler actuating shaft, and graduated means for indicating the proper degree of turning movement of said tumbler actuating shaft.

2. The combination with the fuel feed line of a motor vehicle, of a valve controlling the 55 flow of fuel through said pipe, said valve comprising a casing having a fuel receiving chamber and a fuel inlet passage leading thereto, a partition having a fuel opening 60 therein, a rotatable tumbler disk supported in contact with said partition and having an opening therethrough adapted to register with the aforesaid opening in the partition, a post extending from said tumbler disk, a tumbler operating shaft extending through 65 and projecting from said casing, a disk fast on the end portion of said shaft and having an opening therethrough adapted to register with the opening in the tumbler disk, a tumbler actuating finger projecting from said 70 shaft and adapted to coöperate with said post on the tumbler disk, the valve casing having an outlet passage leading off from the space beyond said disk, means for turning said tumbler actuating shaft, and graduated means for indicating the proper degree of turning movement of said tumbler actuating shaft, and yieldable means for 75 pressing said disks against each other and against the partition.

In testimony whereof I affix my signature.
CLYDE C. CHARLES.
